UNITED STATES PATENT OFFICE.

AUGUST HILDT, OF NEW YORK, N. Y., ASSIGNOR TO LOUIS DRYFOOS & CO.,
OF SAME PLACE.

DESIGN FOR THE ORNAMENTATION OF SKIRTS, LININGS, &c.

SPECIFICATION forming part of Design No. 17,814, dated October 25, 1887.

Application filed September 5, 1887. Serial No. 248,911. Term of patent 7 years.

To all whom it may concern:

Be it known that I, AUGUST HILDT, a citizen of the United States, and a resident of the city, county, and State of New York, have invented a new and ornamental Design for Surface Ornamentation of Skirts, Linings, and other Similar Articles, of which the following is a specification.

My design is for the surface ornamentation 10 of skirts, linings, quiltings, and similar articles; and it consists, essentially, of the vertical rows of lozenge-shaped figures united by cross-lines which form intervening rows of similar figures, all as will hereinafter more 15 fully appear.

In the accompanying drawing I have represented in a single figure a portion (containing all the elements) of my design as it appears when applied upon the article or goods, dotted lines being employed to indicate stitches, and these lines arranged or grouped in accordance with my design, this illustration being deemed sufficient for purposes of this specification.

25 This design is made up entirely of straight lines, and for convenience of description the various parts of the design may be referred to as follows:

A A A are lozenge-shaped figures or parallelograms, of which the longer axis is about twice the length of the shorter, and these figures are placed one above the other distant from each other about the length of the shorter axis, measuring from angle to angle. These 30 constitute one vertical row. B B B are similar figures similarly disposed in a parallel row and distant from those in the other row by about the length of the shorter axis, measuring from angle to angle. Any number of these 35 vertical rows may be employed. The sharper angle of one of the figures A is joined with the like angle of one of the figures B above and one below (but not directly opposite) by straight lines, as *a b, a c, d e, e f*. These straight 40 lines, crossing each other between the vertical

rows already described, form other lozenge-shaped figures or parallelograms alike in size and shape to A and B, but having the longer axis of each turned in a vertical instead of a horizontal position. These are indicated at 50 C C C. Any two consecutive parallelograms, together with the cross-lines extending therefrom, inclose a regular eight-sided figure, as will be seen upon inspection.

The description so far indicates the general 55 principles upon which the lines and figures are grouped. To increase the number of lines and figures in any given space, the same general arrangement is followed for the groundwork, and upon this or to this is added another series of lines precisely like the first, as indicated at the lower part of the figure, wherein, for instance, a lozenge, A', is formed between two lozenges A A by simply extending the sides of the latter. The cross-lines 60 between all the figures being then drawn, as before explained, form a series of small lozenges, and these fill the space between the vertical rows.

The groundwork alone may constitute the 70 whole design in any pattern, or the duplicate thereof may be employed entirely. I prefer to employ both together, the lower part forming a heavy margin for the pattern, while the upper part appears lighter; but the upper and 75 lower parts may be reversed, if desired.

Having now fully described my design, what I claim as new, and desire to secure by Letters Patent, is—

In a design for skirts, &c., the vertical rows 80 of lozenge-shaped figures united by the cross-lines, forming intervening rows of similar figures, substantially as shown and described.

In testimony whereof I have hereunto set my hand.

AUGUST HILDT.
